UNITED STATES PATENT OFFICE.

CONRAD F. ELRICK, OF OMAHA, NEBRASKA.

VEHICLE-POLE TIP.

SPECIFICATION forming part of Letters Patent No. 439,640, dated November 4, 1890.

Application filed September 8, 1890. Serial No. 364,227. (No model.)

To all whom it may concern:

Be it known that I, CONRAD F. ELRICK, a citizen of the United States, residing at Omaha, in the county of Douglas and State of Nebraska, have invented certain new and useful Improvements in Vehicle-Pole Tips; and I do hereby declare that the following is a full, clear, and exact description of the same, reference being had to the annexed drawings, 10 making a part of this specification, and to the letters of reference marked thereon.

Figure 1 of the drawings represents a perspective view of my invention, showing the socket-cap in position to be connected to the 15 pole-tip; Fig. 2, a longitudinal section of the pole-tip and socket-cap in position ready for use; Fig. 3, an end view of the socket-cap, and Fig. 4, a cross-section on line $x-x$ of Fig. 2.

The present invention has relation to that 20 class of vehicle-pole tips provided with means for retaining thereon a socket-cap, such means usually consisting of a stud and groove upon the cap and pole-tip, respectively.

The object of the invention is to improve 25 the means heretofore employed, whereby a stronger and more durable device is provided, and which will present a much neater appearance, and also guard against dirt or grit working in between the joint formed by the pole- 30 tip and cap, which objects I attain by the construction substantially as shown in the drawings, and hereinafter described and claimed.

In the accompanying drawings, A represents 35 the end of a vehicle-pole of the usual construction, to which is connected the metal tip B, the same having a socket C to receive the end of the pole, which is attached thereto by rivets or other well-known means. The outer end of the socket C is much larger in diameter 40 than the tip B, so as to present an annular bearing-shoulder α , against which the end of the socket-cap D abuts when in place, as shown in Fig. 2, thereby forming a tight joint between the shoulder and edge of the cap and 45 preventing sand and grit working in between the tip and cap, as well as presenting a neat appearance to the end of the vehicle-pole. The pole-tip B, at a point where it joins the shoulder α , has an annular supporting-flange

b , which together with the shoulder form a 50° perfect joint and also admit of the socket-cap turning on the pole-tip. Immediately forward of the flange b is a circumferential groove c , and joining this groove is the groove d , which latter extends the entire length of 55 the tip B and has an open end for engagement therewith of a stud e upon the interior of the cap D. It should be noticed that these grooves are on a plane below the circumference of the tip B, so as to present a smooth 60 surface for the interior of the cap D, and a more perfect fitting of the tip and cap is secured.

A further feature of the invention is the extension of the groove d at a point from the 65 groove c to the extremity of the tip, so that the cap will not turn on the tip after being disengaged with the groove c , and thereby prevented from turning until the cap is entirely removed.

When connecting the cap D to the tip B, the former is in position shown in Fig. 1, which will admit of the stud e being engaged with the groove d and the cap slid over the tip until the inner end thereof abuts against the 75 shoulder α and the stud registers with the groove c , after which the cap is turned to bring the stud out of register with the groove d and in engagement with the groove c , and when the cap is turned to the position as 80 shown in Fig. 2 the same will be firmly locked to the pole-tip. In removing the cap D it is turned so as to bring the stud e on line with groove d , when it may be removed. The groove d , extending the entire length of the 85 tip, prevents the cap turning while in the act of removing it.

The cap D is provided with a loop E or any other desirable and well-known means for attaching thereto the holdback straps or chains 90 or the cross-bar or other portions of a harness or attachments used with a vehicle-pole.

Having now fully described my invention, what I claim as new, and desire to secure by Letters Patent, is—

1. The combination, with the socket-cap D, having upon its interior a stud e , of the pole- 95 tip B, having groove c and the longitudinal

groove *d*, the same extending the entire length of the tip, substantially as and for the purpose set forth.

2. The combination, with the socket-cap *D*, having stud *e*, of the socket *C*, having shoulder *a* and flange *b*, and the tip *B*, having groove *c* and the groove *d*, the latter extending the entire length of said tip, substantially as and for the purpose specified.

In testimony that I claim the above I have to hereunto subscribed my name in the presence of two witnesses.

CONRAD F. ELRICK.
